INDIRECT HEAT EXCHANGER

R. Harry Stone, Irvington, and Edwin F. Tilley, Dunellen, N. J., assignors to Titeflex Metal Hose Co., a corporation of New Jersey

Application July 26, 1930. Serial No. 471,034

15 Claims. (Cl. 257—137)

This invention relates to heat exchange apparatus and is particularly adapted for use in connection with devices known as indirect heaters which are used for heating apartments and the like. Such heaters comprise a casing within which a heating element is located, while air is caused to circulate through the casing and, coming in contact with the heater, becomes heated, and after being heated is discharged from the casing into the apartment to be heated.

The most efficient heating medium is, in such devices, a hot fluid such as steam, water etc. While the heater is stationary the heating is mainly confined to certain portions of the apartment, being unevenly distributed in the apartment.

It is the main object of the present invention to provide apparatus of the character described whereby the heat shall be more evenly distributed in the apartment.

It is a further object of the invention to provide means for more efficiently causing the heat to be radiated from the heater.

As ancillary to the last named object, it is a further object of the invention to provide for the more efficient distribution of the air in its relation to the heater.

While a further ancillary object of the invention is to improve the construction of the heater whereby its efficiency in heating the air is enhanced.

Other and ancillary objects of the invention will appear hereinafter.

It will be apparent that the apparatus may also be used for cooling when a cold fluid is supplied to the heat exchanger.

In the accompanying drawings which illustrate the invention—

Fig. 1 is a front elevation of an indirect heater embodying the invention, with certain of the parts broken away and certain other parts shown in section;

Fig. 2 is a view, partly in side elevation and partly in vertical central longitudinal section of the apparatus as shown in Fig. 1;

Fig. 3 is a fragmentary view of a detail of the apparatus;

Fig. 4 is a side elevation, partly in section of sufficient of apparatus similar to that shown in Figs. 1, 2 and 3, to show the application thereto of an improved means for distributing the air through the heater;

Fig. 5 shows, partly in side elevation and partly in section, a structure of corrugated tube whereby the radiating qualities of the heater are increased;

Fig. 6 is a view, partly in elevation and partly in section, of a modified form of radiating tube for the heater;

Fig. 7 is a view, partly in side elevation and partly in section, of a still further modified form of heater radiating tube;

Fig. 8 is a cross section of the strip employed in forming the tube of Fig. 7;

Fig. 9 is a view of a further modified form of heater radiating tube, partly in side elevation and partly in section;

Fig. 10 is a cross section of the strip employed in forming the tube of Fig. 9;

Fig. 11 is a view partly in side elevation and partly in section of a still further modified structure of heater radiating tube;

Fig. 12 is a view partly in side elevation and partly in section of a further modified structure of tube; and

Fig. 13 is a similar view of a still further modified structure of tube.

Referring to the drawings and first to Figs. 1, 2 and 3, the apparatus comprises a metal frame 1 which is stationarily supported in any suitable manner, as for instance, by the suspending rods 2 and 3 secured in the lugs 4 and 5 which are integral with the frame 1.

Within the frame 1 is mounted the heater comprising the upper header 6 and the lower header 7 held in proper relation by being secured to the side plates 8 and 9. The upper tube sheet 10 (being the bottom sheet of the upper header 6) has secured in it, in a fluid tight manner, the upper ends of the corrugated tubes 11, the lower ends of said corrugated tubes being secured in a fluid tight manner in the lower tube sheet 12 (which is the upper sheet of the lower header 7). The corrugated tubes 11 pass through the perforations 13 in the sheets 13 which are distributed between the headers 6 and 7 and secured to the side plates 8 and 9. These plates 13 serve to space and position the tubes 11 intermediate their ends. The corrugated tubes 11 may be of the type which is integrally formed, or may be formed of a strip, for instance as shown in the patent to Louis H. Brinkman No. 1,198,392, patented September 12, 1916.

Within the header 6 is a perforated baffle plate 14.

Communication with a source of supply of steam or other hot fluid is established with the header 6 by means of a pipe 15 rotatably mounted in the frame 1 by means of a ball bearing 16, while the upper end of the pipe 15 is secured to an elbow 17 which in turn is secured in a fluid tight manner to a flexible tube 18 which is in communication with a source of supply of steam or other hot fluid. The lower header 7 communicates with a pipe 19 rotatably mounted by means of the ball bearings 20 in the frame 1, which communicates with an elbow 21 which in turn communicates with the return flexible tube 22 for the steam or other system.

It will now be seen that the live steam will be

transmitted through the flexible tube 18, elbow 17 and tube 15 into the upper header 6 of the heater, whence it will pass through the corrugated tubes 11, thereby losing a large proportion of its heat by radiation, and thence the condensate and remaining steam will pass into the lower header 7 and through the pipe 19 into the flexible return or drain pipe 22. It will be observed that an opening 23 is drilled and tapped in the elbow 21, 5 such opening being adapted to be stopped by a screw plug. Such opening provides a means, by removing the plug, for draining the heater. It will also be observed that the heater, including the headers and communicating pipes, are carried 10 by the pipes 15 and 19 which are rotatably mounted in the frame 1 so that the heater may turn in the frame, the tubes 22 and 18 having sufficient slack and flexibility to allow its turning movement to the extent desired. 15

20 Air is forced through the heater between the tubes 11 by means of a fan 24 fixed upon the shaft 25 of an electric motor 26 of any suitable type and connected and controlled in any suitable and well known way. The fan is mounted within a circular drum or tunnel 27 which is secured to the headers 6 and 7 by means of a sheet metal plate 28 which, with the tunnel, covers, on the fan side, the space encircled by the headers 6 and 7 and the side plates 8 and 9. As the fan revolves 25 the air will be forced between the tubes 11 and out the other side of the heater into the apartment to be heated. The amount and direction of the heated air thus emerging from the heater may be controlled by shutters 29 pivoted in the side plates 8 and 9 at the air exit side of the heater. 30

35 Secured to and extending from the side of the lower header 7 is a bracket 30 to which is bolted the motor 26. The motor, fan and heater, it will thus be seen, comprise a unit which is rotatably 40 mounted in the frame 1 by means of the bearings 16 and 20. To cause this unit to oscillate upon these bearings a pulley wheel 31 fixed upon the shaft of the motor 26 drives, by means of the belt 32, a second pulley wheel 33 which is fixed upon the shaft 34 rotatably mounted in a bracket 35 secured to the side of the bracket 30. Also rotatably mounted in the bracket 30 but upon an axis perpendicular to that of the shaft 34 is a worm wheel 36, fixed upon a shaft 37 and in driving engagement with a worm 38 fixed upon the shaft 34. Also fixed upon the shaft 37 is a crank arm 38' to which is pivoted, at its outer end, a link 39 pivoted at 40 in the stationary bracket 41 mounted upon the stationary frame 1. 45

50 It will now be seen that as the motor 26 rotates and drives the fan 24, it will also drive the shaft 34 and the worm gear 38 thereon, which in turn will drive the worm wheel 36, rotate the shaft 37 and the crank 38'. This obviously will cause the distance between the pivot 40 and the shaft 37 to 55 alternately lengthen and shorten, thereby causing the unit comprising the heater, the fan and the motor to oscillate in the bearings 16 and 20.

60 This oscillation will cause the heated air issuing from the heater to be projected to different parts of the room so that the apartment will be more thoroughly and uniformly heated. The apparatus thus described enables the heat derived from steam or other hot fluid, which is the most efficient manner of heating but which usually radiates its heat from fixed radiators whereby the heating of the apartment is inefficient and non-uniform, to be utilized in such manner that the apartment is efficiently and uniformly heated. 65

70

75

The air propelled by a fan is not uniform over the area of the fan. Usually the fan blades are narrower as the center of rotation is approached, which would decrease the propelling force at the same speed; also the propulsion of the air 80 as the center of rotation of the fan is approached, is decreased because the linear speed of the fan decreases as such center is approached. At the exact center or axis of the fan the speed will be zero so that there is no air propelling force at that point. The air propulsion, both by reason of the usual increase in size of the fan blade and also the increase in linear speed, increases as the distance from the center of the fan increases 85 being, as before stated, nothing at the center of the fan and maximum at its outer circumference. This, in the apparatus shown in Figs. 1, 2 and 3, results in an air flow through the heater which is least at points in line with the center of the fan and increases to a maximum at points substantially in line with the circumference of the fan. The result of this is that the heat extraction by the air from the heater tubes is 90 unequally distributed and inefficient. This is relieved by deflecting air from paths of greater 95 propulsion to paths normally of less propulsion. By this means the propelled air is more evenly distributed, paths normally conveying little or no air being utilized for conveying more air thereby relieving congestion at some points 100 and rarification at others, so that the propulsion of the air through the heater is rendered more efficient, and also by reason of the better distribution of the air in the heater the extraction of heat by the air from the heater (and 105 hence making it available for heating the apartment) is more efficient. It has been found by tests that the amount of heat extracted from a given amount of steam passed into the heater is 110 much greater with a fan equipped as just referred to than with the ordinary fan. 115

Means illustrating an embodiment of apparatus for utilization of the foregoing is shown in Fig. 4 of the drawings wherein the apparatus represented is a side elevation of apparatus similar to that shown in Figs. 1 and 2 but with the addition of a tubular member 42 of frustro-conical shape interposed between the fan 24' and the heater and supported upon the heater unit in any suitable way so that it moves with that unit 12 and maintains a fixed relation to the fan and to the heater. This tubular member 42, it will be seen, has its wider opening adjacent the fan 24' and its narrower opening adjacent the heater mounted in the frame 1'. It will be seen that 13 the air received from the fan into the outer portions of the tube 42 will be deflected from such conditions of greater propulsion toward the axis of the fan, where the propulsion is less and even decreases to zero at the axis, thereby more evenly 14 distributing the propelled air as it passes through the heater and utilizing normally unused paths (at and near the center) for the transmission of air through the heater. The resulting increase in efficiency of the heater has already 15 been referred to. The slope of the deflecting tube 42, as well as its length and diameter will be determined according to the circumstances of each case, such as the desired amount of concentration of air at the center, the structure of the 16 heater, the distribution of air desired in the heater etc., it being obvious that the greater the diameter of the tube 42 at its large end the more and higher speed air will be deflected towards the center, and the greater the slope, that is the 17

greater the difference in area between the large and small ends, the greater will be the deflection and concentration of the air towards the center. Bearing these facts in mind the slope, length and 5 diameter of the tube 42 will be readily varied to suit the desired results under the conditions of the case in hand.

While corrugated tubes are good radiators of heat and thus form good radiating elements for 10 the heat of the fluid passing through them, it is a fact that the heated air lying between the corrugations on the exterior of the tube is pocketed in the groove between the corrugations and does not flow freely away so that the radiation or dissipation of the heat from the tube is impaired. 15 This condition may be greatly improved and the corrugated tube as a radiator of heat may be improved by placing a metallic or other heat conducting fin within the space between the corrugations. This conducts the heat away from its 20 confined space and largely increases the heat radiating capacity of the tube by relieving the congestion of heat which occurs in the space between the corrugations.

25 A device embodying this conception is shown in Fig. 6 of the drawings wherein the corrugated tube 43 is formed by helically disposing a strip having a longitudinal groove and interfolding the edges of adjacent convolutions as described 30 in the Brinkman patent hereinbefore referred to. This tube has the corrugations 44. Between the corrugations is a helically wound strip of metal having a cross section comprising the radially extending fin 45 and foot 46 at right angles thereto. The strip last referred to is 35 wound helically within the groove of the tube 43 between the corrugations 44, and the foot 46 rests upon the tube 43 between the corrugations. The strip comprising the fin 45 and foot 46 may 40 be secured to the tube 43 by soldering, welding or in other suitable ways, or it may be unsecured to the tube 43, merely resting against it.

It will be seen that the fin 45 of the strip conducts the heat of the pocketed air between the 45 corrugations outwardly and dissipates it; also, the strip, including the fin 45 and the foot 46, being in contact with the tube 43 will act to directly conduct the heat from the tube outwardly, which further fact improves the radiation 50 because heated air being pocketed between the corrugations the tube between the corrugations does not so readily radiate its heat.

In Fig. 11 is shown a modified construction of tube having a radiating fin between its corrugations, the corrugated tube 47 being shown, like that in Fig. 6, as being the same as shown in the Brinkman patent hereinbefore referred to. The fin 48, however, instead of being formed of a helical strip of angular cross section, is formed 55 of a flat strip helically wound in the groove between the corrugations of the tube 47. The fin or strip 48 facilitates the dissipation of heat from between the corrugations as already explained in connection with the device of Fig. 6 and may be soldered, welded or otherwise secured 60 to the tube or may simply lie upon it as it is wound thereon.

The heat dissipation or radiation of a corrugated tube may also be improved by means of a fin mounted upon the outer side of the corrugation, and efficiency of the tube as a heat radiator may be very greatly increased by combining the corrugation with a fin upon the outside thereof over what could be accomplished with 75 either the corrugation or the fin alone. A cor-

rugation increases the radiating surface of the tube exposed to the air and so increases its radiation. Upon making the corrugations too high, however, the pocketing of air between the corrugations is very largely increased so that there is more efficient radiation if the corrugations are made of moderate depth and a fin of heat conducting material is supplied on the outside of the corrugation. Also the use of the corrugation in combination with the fin on its outside is more efficient than depending upon the height of the corrugation to give the desired heat radiation, for the reason that if the corrugation is made too high the heated fluid in passing through the tube is apt to not penetrate into the extreme recesses of the corrugation, so that radiation from the outer surface of the corrugation is impaired, whereas if the corrugation is made low the heated fluid within it penetrates fully throughout the corrugation and delivers its heat thereto, the fin at the outside of the corrugation acting to conduct away such heat and dissipate it into the surrounding atmosphere. Also it is advisable to limit the height of the corrugation and combine it with a 100 fin as described because a corrugation of too great depth, under some circumstances, too greatly retards the flow of heated fluid through the tube.

An example of a construction of tube having 105 a fin at the outside of the corrugation is shown in Figs. 7 and 8. In this construction a metal strip 49, of cross section as shown in Fig. 8, is wound into a helical shape when the fin portions 50 on the one hand and 51 on the other will lie 110 along adjacent edges of adjacent convolutions, and these fin portions are then secured together by soldering, welding or in any suitable way to form the tube 52 having the corrugations 53 at the outer end of which are the fins 54.

In Fig. 5 is shown a modified construction of 115 corrugated tube having a fin at the outside of the corrugations, this structure including a tube 55 formed from a helically disposed strip of metal having the edges of adjacent convolutions 120 interfolded as in the Brinkman patent hereinbefore referred to, and having the corrugations 56, the fin being provided by a helically disposed metal strip having a right angled section comprising the radial portion 57 and the foot portion 58 which is inserted in the seam of the tube 125 as shown in Fig. 5. The fin strip may be secured to the tube by soldering, brazing, welding or in any suitable way or may be simply inserted with- 130 in the joint without other securing means.

Another structure of tube having an external fin on the outside of the corrugation of a corrugated tube is shown in Fig. 9. This tube is formed from a metal strip having a cross section as shown 135 in Fig. 10, which cross section includes the radial projection 59 on one side of the strip and a similar projection, but with a hook 60 at its outer end, at the other edge of the strip. This strip is helically disposed and the radial edge 59 of one side of the strip is inserted within the hook 60 on the side of an adjacent convolution. The edges of the strips may then be secured together in any suitable manner as by soldering, welding, brazing or other suitable method. A tube 61 is then 140 formed as shown in Fig. 9, having corrugations 62 and fins 63 at the outsides of the corrugations.

It is, of course, a matter of indifference whether the corrugated tube is an integrally formed tube or whether it is formed from a strip or in other 145 75

ways. So long as the tube is corrugated the fin may be combined with it to advantage.

In Fig. 12 is shown, partly in side elevation and partly in section, an integrally formed corrugated tube having a fin located between the corrugations, the said fin being formed of a helical strip of heat conducting material. This strip may be soldered, brazed, welded or otherwise suitably secured to the tube, or it may simply lie in contact therewith.

In Fig. 13 is shown in side elevation and partly in section, an integrally formed corrugated tube having a helical strip of heat conducting material secured to the outer side of the corrugation by soldering, brazing, welding or in any other suitable way, this strip forming a heat radiating fin in conjunction with the corrugation.

While the invention has been illustrated in what are considered its best applications, it may have other embodiments without departing from its spirit and is not therefore limited to the structures shown in the drawings.

What we claim is:

1. The combination with a support, of a unit comprising a fluid heat exchanger and a motor, said exchanger comprising fluid conduits and said unit being turnably mounted in said support, fluid conveying connections connected with said exchanger and adapted to supply heat exchanging fluid to said conduits and means actuated by said motor for turning said unit.

2. The combination with a support, of a unit comprising a fluid heat exchanger and an electric motor, said exchanger comprising fluid conduits and said unit being turnably mounted in said support, fluid conveying connections connected with said exchanger and adapted to supply exchanging fluid to said conduits and means actuated by said electric motor for turning said unit.

3. The combination with a support, of a unit comprising a heat exchanger having fluid conduits, a motor for turning said unit and a fan for blowing air to said exchanger, said unit being turnably mounted in said support, and fluid conveying connections connected with said exchanger and adapted to supply heat exchanging fluid to said conduits.

4. The combination with a support, of a unit comprising a heat exchanger having fluid conduits, an electric motor for turning said unit and a fan for blowing air to said exchanger, said unit being turnably mounted in said support, and fluid conveying connections connected with said exchanger and adapted to supply heat exchanging fluid to said conduits.

5. The combination with a support, of a fluid heat exchanger comprising headers and corrugated tubes therebetween, said exchanger being turnably mounted in said support, fluid conveying connections connected with one of said headers and adapted to supply heat exchanging fluid to said headers and tubes and means for turning said exchanger.

6. The combination with a support, of a fluid heat exchanger comprising headers and corrugated tubes therebetween, said exchanger being turnably mounted in said support, fluid conveying connections connected with one of said headers and adapted to supply heat exchanging fluid to said exchanger, means for turning said exchanger and a fan adapted to blow air between said corrugated tubes.

7. The combination with a heat exchanging element, of means for propelling a fluid toward said element and means for deflecting fluid acted on by said means, towards the axis of said means, the outer side of said deflecting means being spaced inwardly from the circumference of said propelling means.

8. The combination with a heat exchanger, of a fan to blow air towards said exchanger and means for deflecting said air inwardly toward the fan axis, said deflecting means having its outer edge spaced inwardly from the circumference of said fan.

9. The combination with a fan, of a tubular member for deflecting air propelled by said fan inwardly toward the fan axis, said deflecting member having its outer edge spaced inwardly from the circumference of said fan.

10. The combination with a heat exchanger, of a fan blowing air to said exchanger and a tubular member interposed between said exchanger and fan, said member having openings of different sizes at its ends, the opening of smaller size being at the exchanger end and the opening of larger size being at the fan end of 100 said tubular member, said tubular member having its outer edge spaced inwardly from the circumference of said fan.

11. The combination with a heat exchanger of means for propelling air at an interior portion 105 of the propelled air current towards the exchanger on lines converging towards the axis of said means, there being part of the current of propelled air outside the said converging lines.

12. The combination with a support, of a fluid 110 heat exchanger comprising fluid conduits, said heat exchanger being turnably mounted in said support, fluid conveying connections connected with said heat exchanger and adapted to supply heat exchanging fluid to said conduits and means 115 for propelling air to said heat exchanger, said propelling means and heat exchanger being adapted to occupy predetermined relative positions as said heat exchanger is turned.

13. The combination with a support, of a fluid 120 heat exchanger comprising fluid conduits, said heat exchanger being turnably mounted in said support, fluid conveying connections connected with said heat exchanger and adapted to supply heat exchanging fluid to said conduits and means 125 for propelling air to said heat exchanger, said propelling means and heat exchanger being fixed with relation to each other.

14. The combination with a support, of a unit comprising a fluid heat exchanger and an air 130 propeller, said heat exchanger comprising fluid conduits and said unit being turnably mounted in said support, and fluid conveying connections connected with said heat exchanger and adapted to supply heat exchanging fluid to said conduits 135 and a motor adapted to turn said unit.

15. The combination with a support, of a unit comprising a fluid heat exchanger, an air propeller and a motor driving said propeller, said heat exchanger comprising fluid conduits and 140 said unit being turnably mounted in said support, fluid conveying connections connected with said heat exchanger and adapted to supply heat exchanging fluid to said conduits and means for turning said unit by said motor.
